UNITED STATES PATENT OFFICE.

LILBURN T. HOFFMAN, OF PHILADELPHIA, PENNSYLVANIA, ASSIGNOR TO THE DRAPER & MAYNARD COMPANY, OF PLYMOUTH, NEW HAMPSHIRE, A CORPORATION OF NEW HAMPSHIRE.

INFLATABLE PLAYGROUND-BALL.

1,098,384.

Specification of Letters Patent.

Patented June 2, 1914.

Application filed June 1, 1911. Serial No. 630,701.

To all whom it may concern:

Be it known that I, LILBURN T. HOFFMAN, of Philadelphia, in the county of Philadelphia and State of Pennsylvania, have invented certain new and useful Improvements in Inflatable Playground-Balls, of which the following is a specification.

This invention relates to a playing ball which includes an inflatable bladder, usually 10 of rubber, and a tough and flexible case or cover inclosing the bladder, the inflation of the bladder causing it to conform closely to the interior of the case. The material of which the case is made is leather cut in sections of such form as to give the case the desired form, whether spherical or elliptical. The sections of which the case is composed are secured together by stitches. Heretofore the edges of the sections have been 20 turned inwardly and sewed together, their inwardly turned edges forming inwardly projecting ridges which indent the bladder and are liable to injure the same. Moreover, it is necessary, in order to unite the 25 sections as indicated, to first sew them together with their inner sides outward, and then turn the case right side out, this operation involving the expenditure of considerable time and labor. The external surface 30 of a case made as stated is practically smooth, all the ridges or protuberances being on its inner surface, hence the ball, when used in games which require the catching of the ball by the hands, is somewhat elusive.

35 My invention has for its object to provide a case or cover for a ball of the character above stated, which shall be free from the objections above noted, and it consists in the improvements which I will now proceed to 40 describe and claim.

45 Of the accompanying drawings, forming a part of this specification,—Figure 1 represents a view of a ball constructed in accordance with my invention. Fig. 2 represents an enlarged section on line 2—2 of Fig. 1.

The same reference characters indicate the same parts in all the figures.

In the drawings, 12, 12 represent flexible leather sections constituting the case or outer portion of an inflatable playing ball, said case being either spherical or elliptical when inflated, its form being determined by the shape of the sections.

In carrying out my invention, I turn the 55 margin of each section outwardly to form a narrow flange 13, said flange extending entirely around the margin of the section on which it is formed. In assembling the sections, I abut the flanges 13 together as shown 60 in Fig. 2, and unite them by stitches 14 passed through the bases of the flanges, the exposed portions of the stitches occupying the angle formed by the intersection of the outer sides of the flanges with the outer surfaces of the sections.

The usual slit or opening 15 is provided for the insertion of the bladder 16, said slit being formed by interrupting the continuity 70 of the stitches connecting two adjacent sections. The sections between which the slit 15 is formed are provided with holes 17 which receive a lacing 18.

The case or cover made as described, does not require turning after the sections are 75 stitched together, hence, the time and labor involved in making the case is reduced to the minimum. The outwardly projecting flanges form ribs on the exterior of the ball, these ribs enabling the players to 80 conveniently catch and hold the ball. To aid in holding the cover in proper shape and to facilitate catching and holding the ball, I form some of the sections 12 of a plurality of parts, which parts are united to form 85 transverse ribs 19. By reason of the fact that the edges of the sections are turned outwardly, the inner surface of the ball is free from projections or protuberances tending to indent and abrade the bladder. 90

The stitches being located at the bases of the ribs formed by the outwardly projecting flanges and in the angles formed by the intersection of the outer sides of the sections 95 and flanges, are protected against injurious wear.

I claim:

1. In a playing ball, a case or cover adapted to inclose an inflatable bladder, and composed of sections having their edges 100 turned outwardly to form flanges extending entirely around the sections, the flanges of the different sections being abutted together and secured by stitches passing through the bases of the flanges, each pair of abutted 105 flanges constituting an outwardly projecting rib which protects the stitches and facilitates the catching and holding of the ball,

the inner surface of the case being free from bladder-indenting projections.

2. In an article of the class described, the combination with an inflatable inner case, of 5 a sectional outer case having outwardly turned seams uniting said sections forming a plurality of protecting ribs upon the outer surface thereof, substantially as described.
3. In an article of the class described, the 10 combination with an inner inflatable case, of an outer distensible case formed of a plu-

rality of sections of leather united by outwardly turned welt seams forming protecting ribs for the stitching and surface of the case, substantially as described.

In testimony whereof I have affixed my signature, in presence of two witnesses.

LILBURN T. HOFFMAN.
